UNITED STATES PATENT OFFICE.

HENRY IEPSON, OF PHILADELPHIA, PENNSYLVANIA, ASSIGNOR TO ABBOTTS ALDERNEY DAIRIES INCORPORATED, OF PHILADELPHIA, PENNSYLVANIA, A CORPORATION OF PENNSYLVANIA.

COUNTING MACHINE.

Application filed December 5, 1922. Serial No. 605,117.

To all whom it may concern:

Be it known that I, HENRY IEPSON, a citizen of the United States, residing in Philadelphia, Pennsylvania, have invented a 5 Counting Machine, of which the following is a specification.

One object of this invention is to provide an accurate, simple and substantial device for automatically registering the number of 10 articles, such as packages, boxes or cases, passing a predetermined point, and the invention more especially contemplates a novel structure for carrying a register and a counting wheel so that the latter will be 15 properly actuated by the objects whose number is to be determined.

I further desire to provide an automatic registering device including a counting wheel and novel supporting means therefor 20 arranged to permit automatic adjustment of said wheel to suit it to be invariably actuated by the objects passing it, regardless of variations in their position, dimensions and speed of movement.

25 I also desire to provide a registering mechanism particularly adapted for use in connection with a conveyor or runway to count the number of articles carried by or passing through the same, the invention including novel means for insuring a counting wheel maintaining predetermined relation 30 with the registering mechanism with which it is associated.

These objects and other advantageous 35 ends I attain as hereinafter set forth, reference being had to the accompanying drawings, in which,

40 Figs. 1 and 2 are respectively a side elevation and a plan of a counting machine constructed in accordance with my invention;

45 Fig. 3 is an end elevation of the machine shown in Figs. 1 and 2, the supporting structure being in vertical section;

Fig. 4 is an axial section taken through the counting wheel and its associated support;

50 Fig. 5 is a plan of a runway showing counting machines applied thereto in accordance with my invention;

Figs. 6 and 7 are respectively a plan and a side elevation of a second form of my invention;

Fig. 8 is an end elevation, partly in section, further illustrating the device shown 55 in Figs. 6 and 7; and

Fig. 9 is a vertical section on the line 9—9, Fig. 8.

Referring to Fig. 5 of the above drawings, 1—1 represent longitudinally extending frame members associated with or forming part of a suitable conveying device. This conveying device is shown as being an inclined runway having guide rails 2—2 mounted between and respectively adjacent 60 the frame members 1—1. Extending below and between these guide rails is a series of rollers 3—3 and the structure in the present instance is particularly designed as a runway or conveyor for cases *x* containing 65 filled bottles of milk, cream or the like.

For the purpose of registering the number of boxes passing through this runway, I provide the mechanism shown in Figs. 1 to 4 inclusive, which in a typical case consists 70 of a pair of angle brackets 4—4 bolted or otherwise fixed to one of the frame members 1. These brackets have respectively hinged or pivoted to them by bolts 5—5 the two parallel side members of an inverted U-shaped frame 6, made in the present instance of a length of flat bar material having its ends bent parallel to each other and at right angles to its body. A bar in the form of an elongated bolt 7 extends between 75 the parallel side members of this frame, and a suitable spring 8 is connected between this bar and the adjacent guide member 2 so that it tends to swing said frame on its pivots 80 5—5 toward and keep it from moving away 85 from said guide.

At one end of the frame is bolted or otherwise attached an upwardly extending post 9 having rotatably mounted on its upper end a counting wheel 10, there being anti-friction bearings 11 preferably interposed between said post and the hub of said wheel to facilitate its easy rotation. The diameter and positioning of the wheel is such that under the action of the spring 8 it is normally held so that it projects beyond the plane including the vertical side of the guide member 2, into the runway between said guides so as to necessarily be engaged by any box or case passing through the same. 100 Its diameter is such that its circumference 105

is about equal in length to the length of the side of any box or case with which it is designed to cooperate, and preferably its circumference is somewhat less than the length 5 of the said box or case so that the wheel will make a little more than one revolution for each position or other article moving along the conveying device.

Also mounted on the frame 6 is a registering or counting device 12 whose mechanism is operated by the oscillation of an arm 13 projecting from one end thereof. The end of this arm is connected through a link 14 with a pin 15 projecting from the 10 top face of the counting wheel 10 and said link is preferably slotted so that it is free to move longitudinally to a limited extent independently of said pin. It will be understood that the registering device is operated 15 at each complete revolution of the counting wheel; and it has already been pointed out that this counting wheel makes approximately one revolution during its engagement with each article to be counted. Inasmuch 20 as it is impossible to make the wheel of such a diameter that the article to be counted will rotate it through exactly one revolution, I provide means for additionally moving the wheel after each engagement with an article 25 to cause it to assume a position exactly corresponding to one complete revolution. I find it preferable to make the wheel of such a diameter that it will always make a little more than one complete revolution and then 30 to utilize the said additional means for the purpose of turning the wheel backward through less than one revolution to a position exactly corresponding to a net rotary advance of one revolution. As shown in 35 Figs. 1 to 5, this additional means for moving the wheel comprises a spring 16 connected between the pin 15 and a projection 17 on the frame 6. This spring tends to return the counting wheel to and maintain it 40 in a definite position and the periphery of said wheel is preferably formed with a tooth or notch 18 designed to cooperate with a spring- or other suitable pawl 19. This 45 pawl 19 constitutes a stop for limiting the backward movement of the wheel and the stop thereby causes the wheel to assume a definite predetermined angular position after each revolution. The pawl also serves 50 as a means for preventing any accidental backward rotation of the wheel.

With the described arrangement of parts the passage of a box through the runway defined by the guides 2-2 and rollers 3 causes the counting wheel 10 to be engaged 55 by the adjacent side of said box and as the latter moves, the wheel 10 is rotated by reason of its frictional engagement therewith. Owing to the resultant movement of the pin 15, the arm 13 through the link 14 is caused 60 to make one oscillation for each revolution

of said wheel and such oscillation actuates the mechanism of the registering device 12 so that the number displayed in its "units" opening is advanced. The spring 16 acts to insure that the counting wheel 10 shall 70 make a complete revolution after having been turned more than 180° from its normal position and likewise tends to prevent its making more than one full revolution after 75 this has been completed, since as above noted the length of the side of each box is preferably substantially equal to the circumference of the counting wheel. The latter is caused to make one revolution and advance the register mechanism by one unit for each box it 80 passes so that obviously an accurate registration is automatically made of the number of boxes successively engaging the device.

If desired, as shown in Fig. 5, I may 85 mount two similar registering devices on opposite sides of the runway, but this is not customarily necessary as I have found that when arranged as shown, a single device operates with the desired accuracy. It will be understood that as each box moves into engagement with the counting wheel 10, the frame 6 with said wheel and the registering device swings on the pivots 5-5 and said wheel 10 is pressed frictionally into engagement with the side of the box by reason 90 of the action of the spring 8, the guide 2 serving to limit the movement of said parts after the box has passed.

In that form of my invention shown in 95 Figs. 6 and 7 I provide a bar or plate 25 pivotally held at one end by a bolt 26 to a post 27 carried by the frame member 1. Adjacent its other end said bar rests upon the top of a second post 29 and is transversely slotted for the reception of a threaded extension 28 of said post so that it is permitted 100 a limited swinging movement on the pivot bolt 26. The free end of said bar has fixed to it a vertically extending spindle 30, on the lower part of which is rotatably mounted a counting wheel 10a whose periphery is provided with teeth or points 105 so that it will engage and be positively moved by boxes or packages without likelihood of lost motion. Said spindle above the counting wheel 10 is provided with a flange or fixed collar 31 against which a ring 32 is frictionally pressed by a coil spring 33 acting between it and a pair of adjustable nuts 34-34 mounted on the upper end 110 of said spindle.

Said ring has connected to it one end of 115 a spiral spring 35, whose other end is connected to a pin or bolt 36 projecting from the top face of the counting wheel 10a. The bar 25 is at all times acted on by a spring 37 so that said counting wheel 10a is projected into the path of or tends to engage 120 the boxes or cases moving between the guide rails 2-2 and for this purpose an arm 38 is 125

connected to the bar 25 adjacent its pivot bolt 26, one end of the spring 37 being connected to this arm while its other end is connected to a second arm 39 projecting from 5 the supporting structure 1^a.

In this case the registering device 12 is mounted on the swinging bar 25 and has its actuating lever 13 connected by a bolt or pin 40 to one arm of a lever 41 fulcrumed 10 on the top of a post 42 carried by the bar 25 in such position that the second arm of said lever may be engaged by the bolt or pin 36 on the counting wheel 10^a. A spring 43 acts on the lever 41 to normally hold it, 15 with the actuating arm 13 of the registering device, in a definite position.

With the above described arrangement of parts, a box or package moving through the runway engages the teeth of the wheel 10^a 20 whose circumference is of such length as to cause it to be given a little more than one revolution by said package. The tension of the spring 33 is adjusted by the nuts 34 so that it will act on the ring 32 with sufficient 25 force to prevent said ring slipping on the collar or flange 31 until the tension of the spring 35, reaches a predetermined amount. In this way the spring 35 is maintained under tension and the pin 36 is held by the 30 spring against the lever 41. As a consequence, when the counting wheel is turned by reason of its engagement with the side of a box or package, its pin or bolt 36 ultimately comes into engagement with the 35 lever 41 and swings this on its fulcrum in opposition to the spring 43, thereafter releasing said lever with the result that the arm 13 of the counting mechanism is given one oscillation.

Owing to the spring 35, the pin 36 after 40 having been moved past the lever 41, is brought back against the same when the counting wheel 10^a is disengaged by the box. The spring 37 tends to hold the counting 45 wheel in operative engagement with the box so that it will not slip relatively thereto, so that each box passing said counting wheel will impart one oscillation to the lever 13 of the registering device 12 and cause the 50 mechanism of this latter to be moved to the extent of one unit.

From the above description it will be appreciated that my device is not only relatively simple, but is substantial and of such 55 a nature as not to require attention or fre-

quent repair. Moreover it is highly accurate and permits the number of boxes in a day's run for example, to be instantaneously noted by an observation of the numerals displayed by the registering device 12. It will be understood that it is immaterial whether the articles to be counted are positively conveyed past my apparatus or merely move under the action of gravity, since the structure of the conveyor or runway constitutes no part 60 of my invention.

I claim:

1. The combination in a conveying device, of means for registering the number of articles carried thereby, the said means comprising a counting wheel adapted to engage the said articles and to be moved by each of them through approximately one revolution, a device for registering each complete revolution of the wheel, and means for additionally moving the wheel after each engagement with an article to cause it to assume a position exactly corresponding to one complete revolution. 70

2. The combination in a conveying device, of means for registering the number of articles carried thereby, the said means comprising a counting wheel adapted to engage the said articles and to be moved by each of them through a little more than one revolution, a device for registering each complete revolution of the wheel, and means for turning the wheel backward after each engagement with an article to a position exactly 75 corresponding to a net rotary advance of one revolution. 80

3. The combination in a conveying device of means for registering the number of articles carried thereby, the said means comprising a counting wheel adapted to engage the said articles and to be moved by each of them through a little more than one revolution, a device for registering each complete revolution of the wheel, a spiral spring 90 connected at one end to the wheel and tending to turn the wheel backward after each engagement with an article to a position exactly corresponding to a net rotary advance of one revolution, and a frictional connection for the other end of the spring 100 permitting the said end to turn when the tension of the spring exceeds a predetermined amount. 105

HENRY IEPSON.
